UNITED STATES PATENT OFFICE.

LEWIS L. CHAPMAN, ARTHUR D. CHAPMAN, AND CARL C. CHAPMAN, OF CELINA, OHIO.

PROPELLING MEANS FOR DREDGING-MACHINES.

1,192,752.

Specification of Letters Patent. Patented July 25, 1916.

Application filed January 6, 1916. Serial No. 70,688.

To all whom it may concern:

Be it known that we, LEWIS L. CHAPMAN, ARTHUR D. CHAPMAN, and CARL C. CHAPMAN, citizens of the United States, residing at Celina, in the county of Mercer and State of Ohio, have invented certain new and useful Improvements in Propelling Means for Dredging-Machines; and we do declare the following to be a full, clear, and exact description of the invention, such as will enable others skilled in the art to which it appertains to make and use the same.

Our invention relates broadly to improvements in dredging or ditching machines and more particularly to those designed primarily for dry land dredging.

The object of the invention is to provide a simply constructed and efficient mechanism whereby the machine may be propelled forwardly or rearwardly at will without the use of driven wheels traveling either upon the earth or upon trackways.

With this general object in view, the invention resides in certain novel features of construction and in unique combinations of parts to be hereinafter fully described and claimed, the descriptive matter being supplemented by the accompanying drawings which constitute a part of this application and in which:

Figure 1 is a side elevation of an excavating machine constructed in accordance with the invention; Fig. 2 is a front end view with parts removed; Fig. 3 is a plan view of the supporting frame of the machine and the parts carried thereby; Fig. 4 is substantially a central longitudinal section as seen on the planes indicated by the line 4—4 of Fig. 3; Fig. 5 is a top plan view of the propelling mechanism; Fig. 6 is a longitudinal sectional view thereof as seen on the plane indicated by the line 6—6 of Fig. 5; Fig. 7 is a vertical transverse section taken on the planes of the line 7—7 of Fig. 6; Fig. 8 is a perspective view of one of the bearings of the carriage member; and Fig. 9 is a similar view of a part of one of the supporting legs.

Briefly speaking, the invention comprises a frame 1 rendered portable by front and rear trucks 2, a carriage member 3 movable longitudinally along the frame, one or more inclined leg members 4 pivoted to the carriage and capable of being inclined in reverse directions, a foot member 5 to which the lower ends of the leg members are pivot-

ed, and appropriate means for moving the carriage member 3 longitudinally of the frame 1.

Practically the only parts of the frame 1 which are essential to the proper operation of the invention are the two parallel horizontal longitudinally disposed bars 6 which constitute sills upon which all of the dredging mechanism is mounted, said sills having their front and rear ends rigidly secured to appropriate pedestals 7 which are preferably constructed of angle metal but which may vary in design. The pedestals 7 constitute parts of the trucks 2, the remainder of said trucks being in the form of flat skids 8 pivotally connected to the lower ends of the pedestals 7 and preferably having upturned front and rear ends as shown.

The bars 6 may be in the form of I-beams 75 as depicted in the present embodiment of the invention or of any other preferred type, it being essential, however, that they be so constructed as to provide channel-ways 9 extending longitudinally of their inner 80 sides. The channel-ways 9 receive therein appropriately designed rollers 10 which are secured to the opposite ends of transverse rotary axles 11, it being upon these axles that the carriage member 3 is mounted. The 85 member 3 is shown in the present form of the invention as an elongated beam preferably constructed of wood and interposed between the bars 6, the opposite ends of said beam being bolted or otherwise secured to 90 horizontal feet 12 formed integrally with and extending forwardly and rearwardly from transversely disposed channel-shaped bearings 13, these bearings receiving therein the axles 11 which are held against removal 95 by appropriate clips 14 embracing the ends of the bearings.

Preferably secured to the lower side of the beam 3 by the same bolts which anchor the bearings 13 to the upper side thereof, is a 100 pair of horizontal plates 15 having depending longitudinally aligned ears 16 formed integrally therewith, it being between these ears that heads 17 are swiveled upon longitudinal axes 18. It is to the heads 17 that 105 the upper ends of the leg members 4 are pivoted upon transverse axes 19.

The leg members 4 are shown as being constructed of upper sections 20 and lower sections 21 pivoted together upon transverse 110 horizontal rivets or the like 22, the lower sections 21 being preferably provided with

side plates 23 projecting above the pivots 22 as seen most clearly in Fig. 7. The projecting upper ends of the plates 23 and the portions of the sections 20 therebetween, are formed with aligned bores through which removable pins 24 are normally inserted, whereby the leg members 4 become rigid structures. However, for reasons yet to be described, said members may be rendered flexible by removal of said pins 24.

The foot member 5 may be of practically any preferred construction, but preferably comprises a pair of longitudinal parallel timbers 25 to whose under sides transverse angle-iron cleats 26 are secured, these cleats being adapted for engagement with the earth to prevent slipping of the foot member thereon. As clearly shown in Figs. 6 and 7, the lower ends of the sections 21 of the members 4 are provided with laterally extending journals 27 received rotatably in approximate bearings 28 which are bolted or otherwise secured to the upper sides of the timbers 25. However, the pivotal connection between the sections 21 and the timbers in question, might be in any one of a number of forms.

For reasons to be hereinafter clearly set forth, it is essential that some reliable means be provided for first moving the carriage member 3 longitudinally of the frame, and for then shifting said frame upon the carriage member, while the latter remains in a stationary position. As illustrative of one manner of accomplishing the required end, drums 29 driven from the power plant 30 of the machine, are provided, said drums being adapted to wind thereon cables 31 which are trained around sheaves 32 anchored at the ends of the frame 1, and around other sheaves 33 mounted in slots in the ends of the beam 3. Thus, when the clutches 34 of said drums are properly actuated, the power from the plant 30 may be so transmitted to said drums as to move the carriage and frame in the manner above specified.

The foregoing completes the description of the propelling mechanism of the dredge, and it will be obvious that such mechanism might well be applied to machines of numerous types. However, for illustrative purposes, a common type of boom carrier 35 is shown, said carrier being in the form of a horizontally disposed wheel which may be turned at will upon its upright axis by the provision of cables 36 operated by any suitable means. Connected at its rear end with the carrier 35, is a boom 37 carrying a dredging bucket 38 and the usual connections for operating the same, such connections being manipulated in any well known manner from the plant 30.

Used with the parts just described, is a suitably braced A-frame 39 rising from the

front of the frame 1 and equipped with laterally extending inclined vertically adjustable spud legs 40, the lower ends of said legs being spaced from the lower end of the A-frame by suitable bars 41. The vertically movable sections of the legs 40 may be raised mechanically by any preferred means not shown when the machine is to be moved forwardly or rearwardly.

When the machine is to be moved forwardly, the leg members 4 are inclined downwardly and rearwardly as seen in Figs. 4 and 6 and the carriage member 3 is shifted by its operating means to the front end of the frame 1. The operating means in question is now reversed with the result that since the carriage cannot move rearwardly, the entire machine with the exception of said carriage and parts beneath the same, will be moved forwardly. During this operation, the inclined leg members 4 will exert a raising tendency on the machine and will thus prevent excessive friction between the skids 8 and the bottom of the ditch or the like upon which they travel.

If for any reason the machine is to be moved rearwardly, the pins 24 are removed, thereby allowing the foot 25 to be raised and shifted forwardly to incline the leg members 4 in the opposite direction. When the pins 24 are now again inserted, the machine may be shifted as stated.

From the foregoing description, taken in connection with the accompanying drawings, it will be obvious that although the improved features of construction employed are comparatively simple and inexpensive, they will be highly efficient and durable and will fulfil a long felt need in the art to which the invention relates. In conclusion, we wish to state that we have shown and described certain specific features of construction for illustrative purposes, but that we do not wish to be unduly limited thereto, since within the scope of the invention as claimed, numerous changes may be made without sacrificing the primary advantages thereof.

We claim:—

1. In combination, a frame, trucks supporting the same, a carriage member movable longitudinally along said frame, a leg member pivoted at its upper end to the carriage member and capable without detachment of being inclined downwardly toward either the front or the rear end of the frame, an earth engaging foot member to which the lower end of the leg member is pivoted, and means for moving the carriage longitudinally along the frame at will.

2. In combination, a frame, trucks supporting the same, a carriage member movable longitudinally along said frame, an inclined leg member pivoted to and depending from said carriage member, said leg

member having between its ends a joint for allowing it to be moved to reverse its direction of inclination, an earth engaging foot to which the lower end of the leg member is 5 pivoted, and means for moving the carriage member longitudinally of the frame at will.

3. In combination, a frame, trucks supporting the same, a carriage member movable longitudinally along said frame, an inclined leg member pivoted to and depending from said carriage member, said leg member being formed of upper and lower sections pivoted together to allow it to be so moved as to reverse its direction of inclination, 10 means for normally imparting rigidity to the pivotal connection between the two leg sections, an earth engaging foot member to which the lower end of the leg member is pivoted, and means for moving the carriage member longitudinally along the frame at will.

4. In combination, a frame having a pair of parallel longitudinal bars channelled longitudinally on their inner sides, a longitudinally disposed beam between the aforesaid bars, rollers mounted in the channels of said bars and connected by transverse axles carrying the aforesaid beam, front and rear inclined leg members pivoted to and 25 depending from the front and rear ends of said beam, a longitudinally elongated earth engaging foot member to whose front and rear ends the lower ends of the front and rear leg members are pivoted, and means 30 for moving the aforesaid beam longitudinally at will.

5. In combination, a frame including a

pair of parallel longitudinal tracks, rollers mounted on said tracks, transverse axles connecting said rollers, transversely elongated channel-shaped bearings receiving said axles therein, forwardly and rearwardly extending feet formed integrally with the centers of said bearings, a longitudinally disposed beam secured to said feet, front and 40 rear inclined leg members pivoted to and depending from the opposite ends of said beam, an elongated earth engaging foot member to whose front and rear ends the lower ends of the leg members are pivoted, 45 and means for moving the aforesaid beam longitudinally at will.

6. In combination, a portable frame, a carriage member movable longitudinally thereof, means for moving said carriage member at will, an inclined leg member pivoted to and depending from said carriage member, transverse journals carried by the lower end of said leg member, bearings receiving said journals therein, a pair of parallel longitudinally disposed earth engaging bars to which said bearings are secured, and transverse cleats secured to the lower sides 55 of said bars.

In testimony whereof we have hereunto 60 set our hands in presence of two subscribing witnesses.
